UNITED STATES PATENT OFFICE.

WILLIAM A. SMITH, JR., OF NEW YORK, N. Y., ASSIGNOR TO INGERSOLL-RAND COMPANY, OF JERSEY CITY, NEW JERSEY, A CORPORATION OF NEW JERSEY.

VALVE FOR PNEUMATIC TOOLS.

Application filed November 5, 1926. Serial No. 146,394.

This invention relates to pneumatic tools, but more particularly to an improved distributing valve for tools of this type.

The objects of the invention are to obtain 5 a quick and positive action of the valve and to obtain a powerful blow of the hammer piston against the working implement.

Other objects will appear hereinafter and to all of these ends the invention consists of 10 the combination of elements, features of construction and arrangement of parts having the general mode of operation substantially as hereinafter described and claimed and illustrated in the accompanying drawings, in 15 which

Figure 1 is a sectional elevation of a pneumatic tool showing the reciprocatory elements in one of their limiting positions, and

Figure 2 is a view similar to Figure 1 20 showing the valve and the piston in another position.

Referring to the drawings, the tool comprises a cylinder A having a bore B in which is arranged a reciprocatory hammer piston 25 C provided in this instance with a neck C' near its forward end. A free exhaust port D is formed in the cylinder A for exhausting pressure fluid from the front end of the cylinder and is controlled only by the piston C.

A closure for the front end of the cylinder A is provided in the form of a front cylinder washer E which projects partly into the cylinder and has a bore F to receive slidably 35 an anvil block G adapted to transmit the blows of the hammer piston C to a drill steel H supported by a front head J. A plate K interposed between the front cylinder washer E and the front head J acts as a closure 40 for the front end of the bore F and is bored to receive slidably the front end of the anvil block G. The forward portion of the bore F is in this instance enlarged somewhat to 45 accommodate a head L carried by the anvil block G intermediate its ends.

The rearward end of the cylinder bore B is closed by a plate O which also serves as a seat for a valve chest P in this instance arranged at the rearward end of the cylinder. 50

In accordance with the present invention the valve chest P is provided with a longitudinal chamber Q having an enlarged portion R at its forward end.

Within the chamber Q is arranged a differential type distributing valve S having

an enlarged head T which extends into the enlarged portion R of the chamber Q and has front and rearward actuating surfaces T' and T² respectively. In the rearward portion of the valve S is a recess U which is in constant communication with the atmosphere through an exhaust passage V in the valve chest P.

A plurality of ports W are formed through the valve S, preferably near the rearward end thereof, and are adapted to register with a supply passage X leading through the valve chest, the plate O and the wall of the cylinder A to the front end of the cylinder bore B. Radial ports Y leading from the forward end of the recess U through the enlarged head T are adapted to register with a supply passage Z leading from the valve chamber to the rearward end of the cylinder bore B for exhausting pressure fluid from the rearward end of the cylinder A.

Suitable means are provided to utilize a portion of the pressure fluid admitted to the rearward end of the cylinder bore B for throwing the valve rearwardly. To this end a passage b formed in the cylinder A leads from a point rearwardly of the free exhaust port D to communicate with its rearward end with the enlarged portion R of the chamber Q. Within the enlarged head T is formed an expansion chamber c and ports d leading from the expansion chamber c are adapted to communicate with the passage b when the valve is in its forward position to admit pressure fluid into the said expansion chamber c. The exhaust of pressure fluid from the expansion chamber c is effected through a passage e leading from the front end of the chamber Q to a point in the cylinder bore B preferably in the same transverse plane as the exhaust port D.

The admission of pressure fluid to the drill is effected through an inlet passage f in the valve chest P, leading to a port g in the valve chamber between the supply passages X and Z. The means for conveying pressure fluid from a suitable source of supply to the inlet passage f have been omitted from the drawings, but it is to be understood that such means may consist of the usual hose or pipes commonly used for this purpose.

A small passage h in the valve chest P registers at one end with the ports d in the head T to establish communication between

the expansion chamber *c* and the passage *f* for admitting pressure fluid to the expansion chamber *c* for holding the valve after said valve has been thrown rearwardly.

5 In order to prevent the tool from jumping away from the work upon the admission of pressure fluid to the front end of the cylinder, a passage *j* communicating at its rearward end with the supply passage *X* is formed through the front end of the cylinder and through the front cylinder washer *E* to communicate with its forward end with the enlarged portion of the bore *F*, forwardly of the head *L* of the anvil block. In this way, 10 upon the admission of pressure fluid to the front end of the cylinder, a portion of such pressure fluid will pass into the bore *F* and acting against the head *L* of the anvil block will hold said anvil block firmly against its 15 seat until the free exhaust port *D* has been uncovered by the piston *C*, whereupon the pressure fluid from the bore *F* will be exhausted to the atmosphere together with the pressure fluid in the front end of the cylinder. 20

25 In the operation of the device, with the valve in the position illustrated in Figure 1, pressure fluid entering the inlet passage *f* will pass through the port *g* and thence through the supply passage *Z* into the rearward end of the cylinder bore *B* to drive the piston *C* forwardly to deliver its blow on the anvil block *G*. After the piston *C* uncovers the passage *b*, pressure fluid will flow from 30 the rearward end of the bore *B* through said passage *b* and through the ports *d* in the valve head *T* and throw the valve rearwardly.

35 With the valve in this position, the ports *d* will be moved into registry with the small passage *h* so that pressure fluid will flow directly from the inlet passage *f* into the expansion chamber *c* for holding the valve *S* in thrown position. Such pressure fluid admitted into the expansion chamber *c* will then 40 remain therein to hold the valve rearwardly until the piston *C* has returned rearwardly a sufficient distance to enable the neck *C'* to establish communication between the exhaust passage *e* and the exhaust port *d*, whereupon the pressure fluid in the expansion chamber *c* will be exhausted to atmosphere through 45 the channels described. After the pressure 50

fluid in the expansion chamber *c* has been thus exhausted, the live pressure fluid acting 55 against the rearward actuating face *T'* will throw the valve *S* forwardly to again admit pressure fluid through the supply passage *Z* into the rearward end of the cylinder bore *B*.

With the valve *S* in its rearward position, 60 the radial ports *Y* in the head *T* will register with the supply passage *Z* and the pressure fluid in the rearward end of the bore *B* will then be exhausted through these channels 65 and through the recess *U* in the valve and the passage *V* to the atmosphere. Similarly, after the valve has been thrown forwardly, the ports *W* in the valve will be in registry 70 with the front supply passage *X* to permit the exhaust of any pressure fluid or air compressed by the piston from the front end of the cylinder bore *B* through the valve and through the passage *V* to the atmosphere.

I claim:

A pneumatic tool comprising a cylinder 75 having a free exhaust port for the front end thereof, a piston in the cylinder controlling the free exhaust port, said piston having a neck, a valve chest having a valve chamber, supply passages leading from the valve 80 chamber to the ends of the cylinder, a valve chamber having a recess in constant communication with the atmosphere, a head on one end of the valve having opposed actuating surfaces and an expansion chamber, said 85 head also having radial ports, the rearward actuating surface being constantly exposed to pressure fluid for throwing the valve forwardly, ports in the valve to register with the supply passages for exhausting pressure 90 fluid from the ends of the cylinder into the recess, a kicker passage leading from the cylinder and adapted to register with the ports in the head for admitting pressure fluid to the expansion chamber to throw the valve 95 rearwardly, and an exhaust passage leading from the front end of the valve chamber to a point in the cylinder in the same transverse plane as the free exhaust port, communication between the exhaust passage and the free exhaust port being controlled by the 100 neck of the piston.

In testimony whereof I have signed this specification.

WILLIAM A. SMITH, JR.
